UNITED STATES PATENT OFFICE.

FRANK H. PATRICK, OF SOUTH HADLEY FALLS, MASSACHUSETTS.

CREEL-FRAME FOR WARPING-MILLS.

SPECIFICATION forming part of Letters Patent No. 339,684, dated April 13, 1886.

Application filed December 26, 1885. Serial No. 186,712. (No model.)

To all whom it may concern:

Be it known that I, FRANK H. PATRICK, a citizen of the United States, residing at South Hadley Falls, in the county of Hampden and State of Massachusetts, have invented new and useful Improvements in Creel-Frames for Warping-Mills, of which the following is a specification.

This invention relates to creels for warping-mills and to spindle or skewer attachments therefor, the object being to provide for warping, beaming, and other similar machines requiring creels an improved frame on which the bobbins of warp-yarn are hung while the latter is unwound therefrom, and improved means for attaching the bobbin spindles or skewers to said frame, whereby said spindles, though connected by one end to said frame, are capable of having the free ends thereof swung laterally and vertically to allow said free ends to be lifted from their bearings and swung sideways, so that any bobbin may be taken off from the frame or put on without disturbing the position of any other one.

In the drawings forming part of this specification, Figure 1 illustrates in perspective view a portion of a creel-frame having bobbin-supporting devices applied thereto embodying my invention, several bobbins being shown hung on said frame in operative positions, and one thereof being shown with the spindle on which it turns swung from one of its end bearings, as it is in practice, when a bobbin is to be put on or taken off from said spindle. Fig. 2 is an enlarged perspective view of the devices by which the bobbin-spindles are connected to the bars of the frame, showing a portion of a spindle attached to said devices. Fig. 3 is a transverse section of the spindle-block shown in Fig. 2, showing in connection therewith the headed end of the spindle.

In the drawings, A indicates parts of the top and bottom, and one end of a frame of rectangular form, constructed of wood or other suitable material, having a series of vertical spindle-bars, b, fixed in said frame, which bars are arranged in pairs and in such relative positions to each other that the axes of the bobbin-spindles, which are hung horizontally on each pair of said bars, one above the other, as shown, are inclined to the line of the ends of

the frame, in order that the yarn may be conveniently drawn clear of the bobbin-supporting devices. The bars b are made preferably of metal, and may be either solid or made of tubing, and are provided with a series of transverse perforations, 5, as shown, those of the rear line of tubes not being shown in the drawings. The distance which separates the perforations in the bars b is governed by the diameter of the bobbins to be hung thereon.

In bobbin or creel frames for warping-mills as heretofore employed it is customary to hang the bobbin on a loose spindle, which is put through the bobbin, and the ends of the spindle are engaged in suitable upright supports while the yarn is drawn off from the bobbin, the latter turning meanwhile.

In taking off an emptied bobbin from a loose spindle and replacing said bobbin with one full of yarn, or in taking off a bobbin for the purpose of finding and tying up a broken end, it is exceedingly inconvenient to handle such a spindle and bobbin, for the former is easily and frequently dropped out of the bobbin by the operator, and it slips out of place when the latter is placing the bobbin with the spindle in it in place to run; but, by means of my improvements, as herein set forth, the above-mentioned inconveniences are obviated, for the spindle is constantly connected with the supporting devices thereof, while one end thereof is movable to such a degree as is required to permit the bobbin to be placed thereon and removed.

The spindles or skewers c consist of any required number, more or less, only a sufficient number being shown in the drawings to illustrate the construction and arrangement in a creel, certain of said spindles being shown with bobbins e thereon. The spindles c are of the usual proper form to pass through the bobbin from end to end and allow the latter to be rotated thereon, and are provided with a head, 6, on one end, as shown in Fig. 3, and on the headed end of each spindle c is placed a block, v, preferably of metal, although any other suitable material may be used. Said block v is perforated to let the spindle pass through it, and its rear side is countersunk to receive the head of the spindle, as shown. A metallic strap, z, whose central portion is of circular form, has its two ends pivotally se-

- cured to the opposite ends of said block v by a suitable screw or pin, n , passing through each end of said strap into said block, whereby the latter may swing to permit the free end of the spindle c to have a vibratory motion in the plane of the ends of the block v . The strap z is provided with slots w in opposite sides thereof, one of which is shown in Fig. 2, and in that figure the circular dotted line between the said strap and block indicates the position of the bar b when the strap is attached to the latter, as in Fig. 1. To retain said strap, block, and spindle in proper place on said bar, a pin, x , is passed through the said slots w in the strap and through one of said transverse perforations 5 in the bar b , the ends of said pin projecting beyond the side of the strap. By the above-described means of connecting strap z to said bar the strap is free to be reciprocally rotated on the bar to a certain degree, and thereby the free end of the spindle c is permitted to have a vibratory motion in a horizontal plane to permit its said end to be swung away from its bearing, as shown by the position of one of the spindles in Fig. 1. A bearing for the free end of each spindle c is provided on the front row of the bars b by the bracket-bearing o , having a curved recess in its upper side, in which the end of the spindle lies when in operative position, said bracket being secured to the bar by a suitable pin, 7,

passing through the latter and the circular sleeve of the bracket. Thus it is seen that the free end of the spindle c may be lifted up away from bracket o and swung laterally away from the latter, so that a bobbin, e , may be put on or taken off from the spindle, and when the latter has received its bobbin its free end may be lifted, swung around over its bearing on the bracket, and dropped into said bearing, 40 the spindle meanwhile remaining connected with one of bars b .

What I claim as my invention is—

In combination, the frame A, a series of vertical spindle-bars arranged in pairs, having 45 their upper and lower ends secured in said frame, and having transverse perforations therethrough, a series of spindles, c , a connection for each spindle with one of said pair of bars consisting of a block through which the spindle is passed, a strap partially surrounding one of said bars, having slots in its sides and having a pivotal connection with said block, a pin passing through said slots and the bar, and a bracket-bearing for the free end 50 of said spindle secured on the second one of said pair of spindle-bars, substantially as set forth.

F. H. PATRICK.
